UNITED STATES PATENT OFFICE.

JESSE E. KELSEY, OF THERESA, NEW YORK.

DIRECTION INDICATOR.

1,417,251.

Specification of Letters Patent. Patented May 22, 1922.

Application filed February 10, 1922. Serial No. 535,525.

To all whom it may concern:

Be it known that I, JESSE E. KELSEY, a citizen of the United States, residing at Theresa, in the county of Jefferson and State of New York, have invented certain new and useful Improvements in Direction Indicators, of which the following is a specification.

This invention relates to automobile signals, and has for its object to provide a novel, simple and ornamental device, which may be operatively attached to the outside of either a closed or open automobile, and which is operable by the driver thereof, for indicating to traffic officers, pedestrians and other vehicles, that he intends to turn, slow-down or make a stop. A further object is to provide a neat, compact and ornamental device of the class, which may be easily applied, and whose operation is reduced to the simplest terms. And a further object is to provide a direction and stop indicator, wherein the operating mechanism is all concealed and protected from the weather, and which may be made and installed at a small cost.

I attain these objects by the means set forth in the detailed description which follows and as illustrated by the accompanying drawing in which—

Figure 1 is an outer face view of the complete device. Fig. 2 is a vertical section taken substantially on line 2—2 of Fig. 3; showing the target in the extended position for signalling. And Fig. 3 is a central horizontal section taken on line 3—3 of Fig. 1; showing the target in the closed position.

In the drawing, 2 represents the side wall of an automobile body, and 2'—2^a are similar sheet metal plates disposed at the opposite sides of the body.

My improvement consists of the following parts: 3 represents an elongated base, which is mounted on the plate 2 and held in place by screws 3. 3^a—3^b represent similar spaced lugs or standards, which extend horizontally from the base, and may be integral parts thereof, as shown. These lugs 50 are correspondingly perforated to receive a vertical shaft 4, which supports and operates a target 5, by which the signals are given. The target 5 is preferably made of sheet-metal substantially Z-shaped, as best 55 seen in Fig. 3, the long horizontal arm 5' of the Z comprising the target proper, while

the short horizontal arm 5^a is made fast to the shaft 4, by rivets 4'. The rocking of the shaft 4, swings the target through an arc of substantially 90°, as shown by the full and dotted lines in Fig. 3. The shaft 4 is rotated in the direction for extending the target 5' at right angles to the body 2, as shown by full lines in Fig. 2 and by dotted lines in Fig. 3, by means of bevel-gears 4^a and 6 (shown conventionally in Figs. 2 and 3), which are respectively mounted on the shaft 4, and a shaft 6', the latter shaft extending horizontally through the base 3, the body 2, and the plates 2'—2^a, as shown in Figs. 2 and 3. The shaft 6' is manually operable for moving the target into the signalling position, by means of a crank-like handle 6^a, which is preferably disposed inside the car, within easy reach of the driver. 75 The target 5 is returned to the idle position substantially parallel to the outer face of the body 2, as shown by the full lines in Figs. 1 and 3 at the end of the signalling period by means of a coil-spring 7, which is mounted on shaft 4, one end of the spring being made fast to said shaft, while the other end is held by the lug 3^c carried by the standard 3^b. The gears 4^a—6 and shaft 4, as well as the spring 7, are all enclosed by 85 a sheet metal housing 8, which is preferably detachably secured to the base 3 by screws 8'. One side of the housing 8 is cut away to provide an opening 8^a, through which the target proper 5' extends, and this opening permits the said target to be operated, from the idle to the signalling position (as best seen in Fig. 3). Since the signalling periods are of short duration, and recur 90 more or less infrequently, the gears and other parts disposed within the housing 8, are liable to become impaired by rain, snow and dust, which may enter through the normally open side 8^a. In order to protect the said parts during the intervals in which the target is idle (see Figs. 1 and 3), I provide a novel and effective shield or guard 9, which is permanently mounted on the target 5, as best seen in Fig. 3. The shield 9 extends substantially at right angles 105 to the general plane of the target 5', and its free end 9', which is curved, is preferably in frictional contact with the outer wall 8^b of the housing, so that when the target 5 is rotated a quarter turn, for giving the signal, the free end 9' moves in a path that is concentric to the axis of the

shaft 4. The shield 9 not only protects the gears and other parts within the housing from dust, &c., but it braces and steadies the target while it is being moved back and forth. 10 represents a rubber bumper which is carried by the target, and acts as a cushion when the blade 5' is moved to the closed position, by the tension of the spring 7.

In practice, the housing 8 and the target 10 5' are usually painted or otherwise finished like the body of the automobile, and when properly constructed and installed, the indicator presents an ornamental appearance.

My direction indicator is extremely simple in construction and operation. By the provision of the spring 7, the driver of the automobile simply manipulates the handle 6", in the direction for swinging the target arm 5' outwardly against the tension of the 20 said spring, at right angles to the body 2, as shown by the full lines in Fig. 2 and by the dotted lines in Fig. 3, and holds it for a few seconds, and then lets go the handle. The spring 7 then recoils and 25 swings the target 5' in the opposite direction, to the position shown by the full lines in Fig. 3, and holds the target in the latter position until the next signal operation.

Having thus described my invention what 30 I claim, is—

1. In a direction indicator, a shaft, a target secured to said shaft, the attached end of said target having a right angular

bend for disposing the free end portion of the target in a plane parallel to the attached end portion, a shaft disposed at right angles to the first shaft, bevel gears operatively connecting said shafts, a handle for operating said shafts, a housing enclosing the shafts, the gears, and the angular portion of said target, one side of said housing being normally opened, and a curved guard carried by the angular portion of the target and movable within the housing for preventing dust and dirt from reaching the 45 gears.

2. In a direction indicator, a pair of shafts, bevel gears operatively connecting said shafts, an operating handle carried by one of said shafts, a swingable target having an angular-shaped end which is secured to the driven shaft, a housing for said gears and portions of said shafts and for the angular-shaped portion of said target, one end of said housing being normally open, a shield 50 carried by the angular shaped portion of said target and movable entirely within the housing for normally closing the open end of the housing while the target is in the idle position, and a spring carried by the 55 driven shaft for returning the target to the idle position following each operation thereof by the handle.

In testimony whereof I affix my signature.

JESSE E. KELSEY.
